UNITED STATES PATENT OFFICE

CHARLES A. MOORE, OF EDINA, MINNESOTA

APPARATUS FOR PRECOOLING LADING AT SHIPPING POINTS

Application filed January 3, 1927. Serial No. 158,766.

My invention relates to improvements in apparatus particularly, though not exclusively, for pre-cooling lading at shipping points.

Preparatory to shipping via rail, it is desirable to remove the field and animal heat from perishable produce before it is closed up in refrigerator cars for transit.

An object of this invention, is to provide facilities for the temporary storage of produce under conditions wherein the field and animal heat may be in process of extraction therefrom and whereby such process may continue during the loading of such produce in refrigerator cars.

It is also an object of my invention to provide means apart from a car for desirably conditioning and maintaining the atmospheric condition in the car not only before and after the loading and unloading thereof, but during the loading and unloading thereof, as well.

With the foregoing and other objects in view, which will appear in the following description, the invention resides in the novel combination and arrangement of parts and in the details of construction hereinafter described and claimed.

An embodiment of my invention is illustrated in the drawings wherein Fig. 1 is a vertical sectional view taken as on the line 1—1 of Fig. 2; Fig. 2 is a horizontal sectional view taken as on the line 2—2 of Fig. 1; and Fig. 3 is a vertical sectional view taken as on the line 3—3 of Fig. 2.

Reference being had to the drawings, it will be seen that a room structure A provides a room B with side walls 10 and 11, end walls 12 and a floor proper 13. Spaced above the floor proper is a false floor 14 formed of spaced slats or otherwise suitably constructed in perforated form to provide for the passage of air upwardly therethrough from the space 13^a between said floor proper 13 and said false floor 14. Along the side wall 10 of the structure A are doorways 15 fitted with doors 16, said doorways providing access to the room B through which produce may be taken into the room or removed therefrom. The op-

posite side wall 11 is also formed with doorways 17 therein. These doorways 17 preferably are spaced apart a distance equal to the distance between doorways of coupled refrigerator cars, as at 18, and are disposed in elevation so that they will register, respectively, with the doorways of the refrigerator cars located alongside the building structure. For each doorway 17 I provide an accordion-like casing 19, one end of each casing being secured to the outside of the side wall 11 about the margin of its respective doorway 17. Each casing 19 may be collapsed to take position closely against the outer surface of the side wall 11 and may be extended so that the outer end thereof will meet the marginal portion of the doorway of a refrigerator car registering with the doorway 17 about which the inner end of the casing 19 is placed. The usual gangplank 20, used to span the space between the sill of the doorway 17 of the building structure and the sill of the doorway of a car 18 rests within the expanded casing 19 slightly above the bottom thereof. A suitable door 21 of the sliding or other type is provided for each doorway 17 in the side wall 11 of the structure A. When the casing 19 for a particular doorway 17 is extended into position with the outer end thereof meeting the marginal portion of the doorway of the car, the respective door 21 is opened, and when the casing is collapsed, said door is closed.

From the foregoing it will be understood that the casings 19 provide enclosed gangways between the room B and cars 18 disposed alongside the room structure. And with such gangways provided between the room and cars it will be apparent that produce may be trucked into the cars from the room or from the cars to the room without opening either room or cars to the outer atmosphere. Further, if there is any difference between the temperature of the air within a car and the temperature of the air within the room, it will be comprehended that an equalization of temperatures between room and car will take place under gravity; for example, if the temperature

within the room is lower than the temperature within a car, there will be an influx of cold air from the floor of the room through the lower portion of the casing 19 to the car, and a reverse flow of warmer air from the upper portion of the car through the upper portion of said casing to the upper portion of the room.

Within the room, I provide a device for affecting the temperature of the air therein. This device includes an upright casing C disposed transversely of the building structure and substantially midway between ends of the room, said casing extending from a point beneath the floor proper 13 of the room structure A to the ceiling 22 thereof. In the portion of the casing C, I arrange a horizontal partition 23 having perforations 24 therein or being otherwise perforated to permit of the down flow of air therethrough. Extensions 25 of the upper portions of the sides of the casing C together with a bottom member 26 provide a compartment D at the ceiling of the room, which compartment communicates through an opening 27 in the end of said casing C with the air header E provided in said casing between the ceiling of the room and the horizontal perforated partition 23. At either side of the casing C and adjacent the ceiling 22 of the room B is a duct 28, each duct having an elongated opening 29 therein along the ceiling of the room and being fitted with a damper 30 at the open end thereof of which communicates with said compartment D through an opening 31 in the side of the casing. Also communicating with this compartment D is a depending branch duct 32, fitted with a damper 33 and which communicates at the lower end thereof with a long horizontal duct 34 passing above the doorways 17 in the side wall 11 of the room structure A. Said long, horizontal duct 34 is provided at its lower side with openings 35 (Fig. 3), one for each doorway 17. Each of these openings 35 is arranged along the upper edge of its respective doorway and extends from side to side thereof, and a curtain 36, provided for each opening, hangs from the duct 34, being secured at its upper edge along the transverse edges of the opening 35 and also along the inner longitudinal edge of said opening to form a flexible hood or depending extension 55 of the duct 34 adjacent to the upper portion of its respective doorway 17. Within the chamber F, provided in the casing C beneath the horizontal partition 23, are coiled pipes 37 for a temperature affecting medium. Near the lower portion of said casing C and formed in the sides thereof are elongated openings 38, the same providing communications between said chamber F and the space 13^a at either side of the casing.

C between the floor proper 13 and the false floor 14 of the room B.

When a refrigerating medium is passed through the pipes 37 in the chamber F, the air in said chamber, chilled by said medium, descends by gravity and finds its way out from the casing C through the openings 38 into the spaces 13^a between the floor proper 13 and the false floor 14. Affected by the warmer floor 13 and walls of the room structure A and also by the action of warmer air rising about produce stacked upon the false floor 14, the air from the space 13^a between said floor proper 13 and false floor 14 rises through the latter, all of said air, except as hereinafter noted, passing upwardly to the upper portion of the room, whence it is drawn into and through the ducts 28 to the compartment D, whence it passes into the air header E and, thence, downwardly into the chamber F to begin its cycle anew. With a car 18 and with a gangway enclosing casing 19 in place, as shown in Fig. 3, and with the damper 33 in the depending duct 34 open, a part of the cold air issuing through the false floor 14 at the bottom of the room B finds a ready path into the car through the lower portion of said casing 19, such air thus entering the car and rising along the warmer walls thereof and about any warmer produce within the car finds a ready path from the car through the upper portion of the gangway casing 19, thence through the upper portion of the doorway 17 to the hooded opening 35 of the duct 34, whence said air passes along said duct 34, thence upwardly through the branch duct 32 to the compartment D where it meets the incoming air from the ducts 28 and joins the same in completing the cycle of movement.

In the event that a heated medium is contained within the pipes 37 in the chamber F, the movement of air in the casing C, room B and car 18 occurs reversely in the cycles above explained.

To augment the movement of air under refrigeration, I employ within the chamber F of the casing C, beneath the perforated partition 23 therein, a number of downwardly directed spray nozzles 39. A supply of refrigerating liquid is contained in the bottom of the casing C, in a tank G in which said liquid is stored with the surface thereof at a level slightly beneath the lower edges of the elongated openings 38 in the sides of the casing C. Within the tank G and submerged in the liquid therein are coiled pipes 40 for a suitable refrigerating medium. A pump 41 equipped with an inlet pipe 42, dipping into the liquid in said tank, is fitted with a feed pipe 43 connected with said spray nozzles 39. With this pump in operation, refrigerated liquid is pumped from the tank G to the nozzles 39 and

sprayed downward over the coiled pipes 37 and against the surface of the liquid in said tank. The downwardly directed spray from these nozzles 39 stimulates the ingress of air to the chamber F from the air header E and likewise stimulates the egress of air from said chamber F through the elongated openings 38. The floor proper 13 of the room structure A is provided with a 10 gutter 44 at either side of the casing C, adjacent the lower edge of each elongated opening 38, and said floor is sloped downward from the opposite ends of the room structure A to said gutters to provide for drainage, a sewer connection 45 being fitted to each of said gutters. To minimize the loss of splashing liquid through the openings 38 in the casing C, I provide at the upper inner edge of each opening a baffle 15 flange 46.

Supplementing the action of the spray nozzles 39 in stimulating the flow of air in the casing C, room B and a car 18 is a blower 47 situated in the compartment D. When 20 said blower is idle, it does not substantially interfere with the passage of air from the compartment D to the header E, but when said blower is in operation it effectively stimulates the movement of air in the casing C and in the room B and in a car 18.

In use, under refrigeration or heating, the air within the room B alone may be conditioned by gravity or the air within a car 18 may be primarily conditioned by gravity, or the conditioning of the air in both car 25 and room may be concurrently conditioned by gravity. Under refrigeration and supplementing gravity, the use of the nozzles 39 and the use of the blower 47 concurrently or separately may be had to condition the air in the room along or primarily in the car, or concurrently in both room and car.

My invention is highly advantageous in the handling of perishable produce at shipping points. When the loading or unloading of cars is not taking place, that produce placed in the room B is prepared or held in condition for shipment by suitably conditioning the air in the room. When cars 40 are spotted alongside the room structure, the gangway casings 19 may be extended into positions of use. If the cars are empty, they may be prepared for transit before the loading thereof, or while the loading is being accomplished and without materially altering the condition of the lading, such preparation may take place. If the cars 45 are loaded and labor for unloading unavailable or the time for unloading inopportune, the lading within the cars may be held in its then condition or the process of altering that condition initiated. And, of course, the maintenance of the condition of said lading or the continuance of the process in 50 altering the condition thereof may be had

during the unloading of the lading, when it becomes convenient to unload. Thus it is evident that my invention provides for the desirable preservation of perishable produce and the handling of relatively large quantities thereof in minimum time and with a minimum of storage space and transportation equipment. In short, labor, building and transportation costs are minimized in attendance with the handling of perishable 70 produce, in the maximum, under conditions 75 promoting the preservation thereof.

Changes in the specific form of my invention, as herein disclosed, may be made within the scope of what is claimed without departing from the spirit of my invention. 80

Having described my invention, what I claim as new and desire to protect by Letters Patent is:

1. In a structure forming a room having a doorway, a casing adapted to provide an enclosed gangway between said doorway and the doorway of a refrigerating car alongside said structure, an air refrigerating device, a blower associated with said device 85 for circulating air in the room and subjecting it to the action of said refrigerating device, and a duct communicating at one end with the intake of said blower and at its other end with the upper portion of said 90 casing.

2. In a structure forming a room having a doorway therein, a gangway casing extending outward from the doorway in said structure, said casing being adjustable to 100 meet the marginal portions of a doorway in a car disposed alongside said structure, and means for affecting the temperature of the air within said room, said gangway casing providing a horizontal air passageway 105 through which upper and lower gravitating currents of air may pass, in opposite directions, between room and car.

3. In a structure forming a room having a doorway therein, a casing providing an enclosed gangway between said doorway and the doorway of a car alongside said structure, said gangway casing providing an air passageway for a lower current of cold air from the room to the car and an upper current of warmer air from the car to the room, a refrigerating device, means for receiving the air in said upper current and subjecting it to the action of said refrigerating device, and means for directing the 110 air, affected by said device, into the room at the lower portion thereof.

4. In a structure forming a room having a doorway therein, a casing providing an enclosed gangway between said doorway 115 and the doorway of a car alongside said structure, said gangway casing providing an air passageway for a lower current of cold air from the room to the car and an upper current of warmer air from the car 120

to the room, a refrigerating device, means for subjecting air to the action of said refrigerating device, said means being adapted to take its supply of air from said upper current and also from the upper portion of the room, and means for directing the air, affected by said device, into the lower portion of the room.

5. In a structure forming a room having 10 a doorway therein, a casing providing an enclosed gangway between said doorway and the doorway of a car alongside said structure, said gangway casing providing an air passageway for a lower current of 15 cold air from the room to the car and for an upper current of warmer air from the car to the room, an air refrigerating device, a blower associated with said device for introducing air thereto, a duct having an 20 opening therein to receive said upper current of air, said duct communicating with the intake of said blower, and a second duct having an opening to receive air from the upper portion of the room, said second duct 25 also communicating with said intake of said blower, said refrigerating device being in communication with and adapted to supply refrigerated air to the lower portion of the room.

30 6. In a structure forming a room having a doorway therein, a casing providing an enclosed gangway between said doorway and the doorway of a car alongside said structure, said gangway casing providing an 35 air passageway for a lower current of cold air from the room to the car and for an upper current of warmer air from the car to the room, an air refrigerating device, a blower associated with said device for introducing air thereto, and a duct having an 40 opening therein to receive said upper current of air, said duct communicating with the intake of said blower, said refrigerating device being in communication with 45 and adapted to supply refrigerated air to the lower portion of the room.

7. In a structure forming a room having a doorway therein, a casing providing an enclosed gangway between said doorway and 50 the doorway of a car alongside said structure, said gangway casing providing an air passageway for a lower current of cold air from the room to the car and for an upper current of warmer air from the car to the 55 room, an upright air refrigerating device adapted, by gravity, to take in air at its upper portion and discharge air from the lower portion thereof into the lower portion of the room, a duct opening at its lower end 60 to receive air from said upper current, said duct leading upward to the upper ingress portion of said refrigerating device.

8. In a structure forming a room having a doorway therein, a casing providing an 65 enclosed gangway between said doorway

and the doorway of a car alongside said structure, said gangway casing providing an air passageway for a lower current of cold air from the room to the car and for an upper current of warmer air from the car to the room, an upright air refrigerating device adapted, by gravity, to take in air at its upper portion and discharge air from the lower portion thereof into the lower portion of the room, said refrigerating device including a downwardly directed spray nozzle, the spray therefrom serving to supplement the action of gravity and stimulate the flow of air in said refrigerating device and in said room and car.

9. In a structure forming a room having doorways therein, casings, one for each doorway, each casing providing an enclosed gangway between its respective door of said room and the doorway of a car alongside said structure and, further, providing an air passageway therethrough for opposed upper and lower currents of air, and an air duct common to and communicating with each casing, said duct being adapted to convey the air constituting like currents in said casings.

10. In a structure forming a room having a doorway therein, a casing providing an enclosed gangway between said doorway and the doorway of a car alongside said structure, said gangway casing providing an air passageway therethrough for opposed upper and lower currents of air, an air duct having an opening therein adjacent to the top of the doorway of said room, and a baffle curtain forming a depending extension of said duct, said curtain partitioning said upper current of air from the interior of the room.

11. In combination, a structure forming a room for perishable lading, means for affecting the temperature of the air within the room, said structure having a doorway in the side thereof through which lading may be carted to or from a car alongside said structure via a side door in said car, a gangway casing adapted to enclose the space between the doorway of said structure and a door of a car, said gangway casing providing a horizontal way for the passage of upper and lower currents of gravitating air, one from room to car and the other from car to room.

12. In combination, a structure forming a room for perishable lading, means for introducing refrigerated air into the room at the lower portion thereof and for taking off the warmer air from the upper portion of the room, said structure having a doorway in the side thereof through which lading may be carted to or from a car alongside said structure via a side door in said car, a horizontal gangway casing adapted to enclose the space between the door of said

structure and a door of a car, said gang-way casing providing an air passageway for gravitating air currents, one, a lower current of cold air from the room to the car, and the other, an upper current of warmer air from the car to the room.

5 In testimony whereof, I have signed my name to this specification.

CHARLES A. MOORE.
